DRILL STEEL ROD

Charles Percy Hammond and Allister McKenzie Cameron, Welland, Ontario, Canada, assignors to Atlas Steels Limited, Welland, Ontario, Canada, a company of Canada

Application July 25, 1945, Serial No. 606,900

1 Claim. (Cl. 76—108)

1

This invention relates to drill steels used for rock drilling, etc., and pertains in particular to hollow drill steels such as used in the mining fields.

Drill steels of this kind are subjected in use to a combination of flexural, vibratory and shock stresses which result in the ultimate fatigue of the steel. As a result, therefore, breakages occur after a period of use and in many cases before a reasonable period of use has been attained. In some cases it is possible to use broken lengths of the steel providing that they break towards the end of a section, thus leaving a length of rod which can be employed usefully.

Drill steel rods of octagonal and hexagonal cross-section are most widely used, the octagonal shaped rod being commonly known as "quarter octagon" because of the fact that it is of generally square character in cross-section with the corners substituted by flat narrow portions disposed at an angle to the plane of the four main sides of the rod, and these shapes are formed by rolling after the steel billets have been reduced by successive rollings to a predetermined size. However, due to the fact that on diagonally opposite corners of the hexagonal and octagonal drill rod sections, it is impossible to cause the rolls to engage the surface of the corner. These corners when produced are pitted and roughened and contrast somewhat with the opposite corners. As a result, therefore, fractures occur which can be traced primarily to this cause since a roughened or pitted surface will lead to strain and fracture. Moreover, due to the relatively sharp corners that are formed as a result of the corner formations of hexagonal and quarter octagon drill sections, such corners are liable to nicking and scoring in use and accordingly this leads very often to fracture when the section is under strain of use.

These disadvantages are largely avoided by the present invention.

It is an object of the present invention to provide a new drill rod section which will be subject to longer life and lessened hazard of fracture.

A further object of the invention is to provide a drill steel section which in terms of substantially similar or slightly less cross-sectional area as compared to quarter octagon or hexagonal drill sections will provide a greater surface area having the effect of reducing the average unit stress.

A further object of the invention is to provide a drill steel section of this kind which will pro-

2

vide an actually greater perimeter formed by an alternating concave-convex contour and smooth curved surface to increase resistance to fatigue and shock effect by a wider dissipation of stresses at the surface of the section or rod.

A further object of the invention is to provide a drill section of generally hexagonal or octagonal cross-section eliminating all sharp or near sharp corners.

10 A further object of the invention is to provide a drill section of this kind in which the section will be basically stiffer in terms of deflection under given load in comparison to a drill section of hexagonal or quarter octagon section of equal cross-sectional area.

15 A further object of the invention is to provide a drill section of this kind wherein the corner areas of the drill section will be less roughened or pitted than in the case of conventional hexagonal or quarter octagon drill sections.

20 A still further object of the invention is to provide a drill steel section of this kind which is less sensitive to unavoidable use in handling and operation such as to reduce nicks, scores and wear which ordinarily result in conventional drill steel sections.

25 A still further object of the invention is to provide a drill steel section which, due to the provision of an alternating concave and convex surface, will provide for a greater shank life by permitting the grit and particles of steel to work out of the drill chuck during drilling operations.

30 A still further object of the invention is to provide a drill steel section which, due to its contour, will cause said section to be more completely under compression during the rolling operation and which will largely eliminate roughened surface areas which occur in conventional drill steel.

35 With these and other objects in view, the invention generally comprises a drill steel rod or bar formed with an alternating concave and convex contour, which may be produced in a hexagonal or octagonal form and in which the corners of the section are rounded to provide a continuous

40 substantially smooth surface throughout the perimeter of the section and an increase in diameter along the diagonal lines extending between the corners and through the center of the section, and producing in result a drill steel section of greater durability as will be clearly understood by reference to the following detailed specification taken in conjunction with the accompanying drawings.

In the drawings:

55 Fig. 1 is a cross-sectional view of a conven-

tional quarter octagon drill steel as commonly used.

Fig. 2 is a cross-section of a drill steel rod according to the present invention of a shape generally corresponding to quarter octagon shape of the prior art.

Fig. 3 is a transverse section taken through a quarter octagon drill steel of the prior art showing it located in the chuck of a drill.

Fig. 4 is a cross-sectional view similar to Fig. 3 but taken through a drill steel section of the present invention to show it inserted in a drill chuck of corresponding size to that illustrated in Fig. 2.

Fig. 5 is a fragmentary perspective view of a drill steel section of the kind shown in Fig. 2.

Fig. 6 is a fragmentary perspective view of a drill steel section according to the present invention substantially corresponding to the hexagonal type of drill steel section of the prior art.

Figure 7 shows a quarter octagon drill steel section of the prior art passing through the forming rolls, the latter being illustrated fragmentarily; and

Figure 8 is a similar view to Figure 7 showing a fragmentary schematic view of a drill steel section of the present invention passing through the forming rolls, the latter being shown fragmentarily.

Referring to the drawings, A indicates a drill section of the prior art commonly known as the quarter octagon section, and B indicates a drill section according to the present invention which may be generally termed a "clover leaf" section by reason of its similarity to a four leaf clover if the corner sections were brought in along the diagonals towards the center. As indicated in Figs. 1 and 2, these sections have a generally rectilinear character and, as will be noted by the arrow lines A in each case, their overall cross-sectional dimensions are the same. Similarly, by reference to Figs. 3 and 4, it will be noted that both sections will fit into the socket of the drill chuck C, even though the dimensions of the clover leaf section, of the present invention, when measured along the diagonals of a cross-sectional contour thereof, are of greater length than the diagonals of the quarter octagon section as referred to hereinafter. This is due to the fact that some clearance is permitted in the drill chuck, particularly at the corners for insertion of the conventional drill rod section. This is equally true in the case of the hexagonal drill steel section.

The approximate appearance of the drill rod sections according to the present invention is illustrated in Figs. 5 and 6 and it will be understood that in describing the comparative merits of the quarter octagon with the new clover leaf section of the present invention, that corresponding remarks apply generally to the hexagonal drill rod section according to the present invention in comparison to that of the prior art.

Referring particularly to Fig. 2, it will be noted that the clover leaf drill steel section according to the present invention is given an outer contour, alternatively concave and convex, with rounded corners 10 formed from equal radii, the concave portions being indicated by the numeral 11 and the convex portions in addition to the corners 10 preferably including the intermediate convex portion or rib 12. These portions occur alternately around the perimeter of the section and each extends longitudinally of the section and parallel to one another throughout its length.

This formation provides a completely smooth though undulating surface throughout the perim-

eter of the section and avoids any sharp or nearly sharp corners particularly subject to nicking and scoring during handling and in operation. Accordingly one contributing cause of fracture is largely eliminated. Of even more importance, however, is the reduction to the minimum of pitted or roughened surfaces on opposed corners of the drill rod section which are a contributing cause to fracture and failure of drill rod section.

10 This is aptly illustrated by reference to Figs. 7 and 8.

The drill rod section according to the present invention will permit a greater area of contact between the forming rolls and the surfaces of the drill rod section which places a larger portion of the section under compression during the final rolling operations and largely eliminates pitted or rough areas at the surface metal on opposed corners where in normal practice it is impossible to obtain roll contact.

20 Referring to Fig. 7, the quarter octagon section A of the prior art is passing between the forming rolls 13 and 14 formed with conical areas 15, to give the flat side contour to the section, and the cylindrical portions 16 which give the flat corner contour on two opposed corners of the section. The remaining two opposed corners generally indicated by the numeral 17 are formed without roll contact as is clearly illustrated and in result, the metal here is not under complete compression and rough surface areas along these corners are formed throughout their lengths.

25 In contra-distinction to this, it will be noted particularly by reference to Fig. 8 that the section B according to the present invention permits a roll contact by the fluted surfaces 15a of the rolls 13a and 14a, substantially throughout its entire area except for a very minor strip indicated by the numeral 18. Thus, substantially all the section is under compression during the final rolling operations and the opposed roughened surfaces as created by the prior art above referred to are largely eliminated. It will be apparent, therefore, from this that a contributing cause to fracture and fatigue is largely eliminated. Accordingly, therefore, the drill rod section provides an improvement over that of the prior art in this important consideration.

30 In addition, however, further advantages stem from the improved contour. On the one hand it is clear that the alternate concave and convex contour provides an increased perimeter which provides a greater surface area having the effect of reducing the average unit stress and it increases resistance to fatigue and shock brought about by a wider distribution of stresses at the surface of the section.

35 The outside dimensions of this section substantially correspond with the overall outside dimensions of the quarter octagon section illustrated in Fig. 1, yet it will be noted that by providing the rounded corners 10 formed from equal radii that the diagonals of the cross-section of this rod indicated by the dotted lines 19 are longer than the corresponding diagonals of the quarter octagon section of the prior art and as is clearly indicated when locating, in Fig. 2 by way of dotted lines 20, the position of the flat corners 21 of section A which position they would assume if section A were superimposed directly on top of section B. This achieves a further advantage by increasing the operational strength and stiffness of the section, of importance particularly when the drill rod section is under flexural stress during operation.

Finally, it should be noted that at least three further advantages are attained. In terms of deflection of the drill rod section of the present invention under a given load, the sections produced according to the present invention are basically stiffer than those of the prior art, having a corresponding cross-sectional area. The formation of the bore of hollow drill steel section is maintained more symmetrically than in the case of the prior art, while the grooves in the exterior surfaces of the drill rod section form passages between the head of the drill rod and the surrounding socket of the drill chuck which receives it, thereby permitting particles to dislodge which normally tend to accumulate in the chuck and having an abrading action on the drill rod.

The drill rod section of the present invention may be produced with equal facility to that of the prior art, while achieving the advantages outlined.

What we claim as our invention is:

A drill steel rod having at least four sides of equal width disposed at an angle to one another and having an undulating perimeter of a series

15
20
25

of concave convex curves of equal radius, said section having a dimension measured along the diagonals extending transversely of the rod between opposed corners thereof greater than 5 standard rods of equal side width and angular relation which have substantially flat surfaced corners, said greater dimension being equal to twice the difference between a chord theoretically drawn from the terminal ends of said rounded corners and the periphery of the curve of said rounded corner at its point of intersection with said diagonal.
